UNITED STATES PATENT OFFICE.

HARRY M. KORETZKY, OF NEW YORK, N. Y.

TERMINAL CLIP.

Application filed May 7, 1923. Serial No. 637,304.

This invention relates to terminal clips, that is, spring-friction strip-metal devices adapted to be connected to a battery terminal and having spring-biassed parts such 5 that a wire or other elongate electrical conductor may be instantaneously and easily gripped by the clip and removed therefrom with equal facility, yet always when gripped by the clip to be securely and reliably held, 10 both mechanically and for good electrical contact.

An important object sought to be attained by the present invention, will be best understood if the construction and action of the 15 well-known and widely adopted Fahnestock terminal clip is recalled, and particularly the hook-and-hook structure characteristic thereof, with its observed action so far as ease of mounting and demounting a conductor is concerned.

It is, then, the important object of the invention to provide a terminal clip wherein there is entirely eliminated a rigidity and stiffness of the spring-friction conductor-gripping elements proper such that the connecting up of a conductor is not a difficult 25 and sometimes annoying task, and particularly not a task such that the fingers of the one attempting to attach the conductor are 30 bruised or pained by the pressure required to separate said elements for insertion of a length of the conductor. I have discovered that to attain this end it is necessary to consider relatively unimportant whether or not 35 the terminal clip is made of a single unitary piece of strip metal or of a plurality of such pieces. And I prefer to embody my new clip in a form containing two such 40 lengths of strip metal; especially since I have further discovered that the manufacturing cost of the clip is not thereby materially increased, due to metal-saving, small 45 initial die expense, and the exceedingly nominal cost of riveting or otherwise securing together said two lengths.

A further important object of the invention is to provide a clip such that the same may be constructed at a minimum of expense but for perfectly reliable action, and yet the 50 conductor-gripping elements need not both be hook elements, and indeed, need not either one be a hook element.

A further object of the invention is to provide a clip as just characterized, but one

wherein the lazy-U spring-bow feature characteristic of the Fahnestock clip is preserved, and yet a clip sharply distinguished from said clip last mentioned in that while the upper leaf of such U carries the conductor-gripping element to take the underside 55 of the conductor, such conductor may be engaged with the clip by a sidewise movement of the conductor rather than necessarily by an endwise movement thereof.

The invention will be more clearly understood from the following description, when taken in connection with the accompanying drawing, showing a preferred one of the many possible embodiments of the invention.

In said drawing:

Fig. 1 is a perspective view of a battery carrying one of such embodiments, with the clip there shown gripping a conductor and having its shank bent to show one possible mounting, of any clip according to the invention, on one terminal of a battery;

Fig. 2 is a top plan view of the clip of Fig. 1, detached from the battery and conductor;

Fig. 3 is a vertical section, taken on line 80 3-3 of Fig. 2.

Preliminarily viewing the entire drawing, it will be seen, referring to Fig. 1, that a conductor engaged by the clip is indicated at 7, and that a battery cell of a familiar 85 type is indicated at 8, such cell having the pair of terminals 9 and 10.

It will be seen further that the illustrated embodiment of the new clip comprises two separate lengths of strip metal, as spring 90 brass.

The strip carrying the lazy-U (by which is meant a spring-bow U lying away from the vertical) is marked 11, and the other strip is marked 12.

In the case of the embodiment of Fig. 1, (a) the strips 11 and 12 are secured together by a single rivet 13 and a punching 14, (b) the strip 12 is slotted at 15 for receiving for play therein an operating tongue 100 16 on the other strip, the strip 11, (c) the strip 12 carries a bent-over terminal element 17 for gripping the upper side of the conductor 7, (d) said element 17 is bent toward the bowl of the U, (e) the solderable 105 or otherwise attachable shank-portion 18 of the clip is the lower end of strip 12, and (f) the upper leaf 19 of the U-bow takes the

underside of the conductor 7, and has a plane upper surface and one uninterrupted by any removed metal.

It will be noted that the clip has this important characteristic, that the hook-over elements 17 for the conductor 7, while bent in relation to the bowl of the U-bow, are nevertheless bent so as to facilitate a sidewise engagement of a conductor 7 with the clip, and yet the conductor-gripping elements of the clip are always easily separable to a very large extent to make practically as easy an endwise engagement of such conductor. This latter novel and important advantage is due in part to the long leverage existing between the free end of the operating tongue 16 and the point of bend at the bowl of the U-bow and in part to the fact that compactness of general structure is preserved and yet to attain very wide separation of the conductor-gripping elements the upper and lower leaves of the U need not be brought very close together at any point.

It will be noted further that the clip has another exceedingly important characteristic, to wit, that while the clip has at least one plate element (19) for gripping the conductor, such plate element need not be bent transverse to its length at any point to present in effect a hook element, that is, one carrying a transverse groove or depression at any point.

As hereinabove indicated, wide variations may of course be resorted to, within the scope of the following claims.

35

I claim:

1. A terminal clip, comprising a strip having a free member projecting at an angle from its upper end and having a slot therein adjacent the said member, and a second strip having one end secured to the first-mentioned strip and its free portion constituting a bow spring, one end of the spring extending under the angular member of the first strip and projecting through the slot thereof and constituting a finger engaging portion, the angular member and the spring constituting gripping jaws between which a conductor can be passed sidewise.

2. A terminal clip, comprising a strip having a free member projecting at an angle from its upper end and having a slot therein adjacent the said member, and a second strip having one end secured to the first-mentioned strip and its free portion constituting a bow spring, one end of the spring extending under the angular member reduced in width to form a tongue projecting through the said slot and constituting a finger engaging portion, the angular member and the spring constituting gripping jaws between which a conductor can be passed sidewise.

HARRY M. KORETZKY.
